UNITED STATES PATENT OFFICE

EUGENE HIGGINS, OF JACKSON, MICHIGAN

BRAIDING MACHINE

Application filed August 11, 1930. Serial No. 474,420.

The main objects of this invention are:

First, to provide a braiding machine which may be operated at high speeds with a minimum of shock and vibration of the parts.

Second, to provide a braiding machine in which the parts may be largely formed as stampings and assembled into a strong durable structure.

Third, to provide a braiding machine having these advantages which is very economical in structure.

Fourth, to provide in a braiding machine an improved automatic stop mechanism.

Objects pertaining to details and economies of my invention will definitely appear from the description to follow. The invention is defined in the claims.

A structure which embodies the features of my invention is clearly illustrated in the accompanying drawings, in which:

Fig. 1 is a side elevation of my improved braiding machine, a portion of the take-off drum being broken away.

Fig. 2 is an enlarged horizontal section on line 2—2 of Fig. 1.

Fig. 3 is an enlarged fragmentary view mainly in vertical section on line 3—3 of Figs. 2 and 4.

Fig. 4 is a detail section on a line corresponding to line 4—4 of Fig. 3.

Fig. 5 is an enlarged detail view mainly in vertical section on line 5—5 of Figs. 2 and 6.

Fig. 6 is a horizontal section on line 6—6 of Fig. 5.

In the embodiment illustrated I provide a frame consisting of corner uprights 1 arranged through and secured to the bed 2 which constitutes a connecting member for the uprights adjacent their lower ends. The uprights are connected at their upper ends by the top plate 3.

A take-off drum 4 is mounted on a shaft 5 carried by the supports 6. This take-off drum has a gear 7 connected to the vertical shaft 8 by a train of gears 9. The shaft 8 is connected to the motor 10 which is mounted on one pair of the uprights by means of the belt 11 coacting with the pulley 12 on the shaft 8. The pulley is connected to the shaft

through a clutch shown conventionally at 13. These parts are not further detailed as the details thereof form no part of my present invention.

The bed 2 is formed of a pair of plates 14 and 15 having telescoping flanges 16 and 16' at their edges. The plates are held in spaced relation by the shouldered spacing spools 17. The spools also constitute supports for the posts 18.

These posts are provided with heads 19 at their upper ends and are shouldered at 20 to engage the clamping members 21 arranged within the inner cam members 22, which is, in turn, nested within the cam member 23. The posts are also provided with clamping nut 24 below the bed so that the cam members are clamped upon the bed.

These cam members in the embodiment illustrated are cupped stampings, their flanges 70 being conformed to provide suitable cams.

The bed is provided with holes 25 which are engaged by lugs 26 on the outer cam members, these holes being positioned in the upper plate of the bed to properly position the cams. To position the inner and outer cams relative to each other, the outer cams are provided with recesses 27 and the inner cam member with lugs 28, these lugs and recesses being located so as to position the pairs of cams relative to each other.

By this arrangement the outer cams may all be formed by one die, that is, they are all alike, and the inner cams are also all alike, so it is merely a matter of positioning them relative to each other on the bed to properly control the coacting mechanism, and they are clamped in place by the posts.

The clamp members 21 also serve as end thrust members for the rotary heads designated generally by the numeral 29. These heads consist of hubs 30, top plates 31 and bottom plates 32 held in properly spaced relation by the spacing sleeves 33 arranged between the plates on the hub. The gears 34 are also mounted on the hubs and are held in properly spaced relation to the bottom plate 32 by the rings 35 and rings 36 arranged below the gears. The gears are arranged in meshing relation.

The plates and gears are preferably stampings and a pressed fit on the hub so that they are held in proper assembled relation thereon without other attaching means. The lower 5 end of the hub and the lower ring 36 constitute an end thrust bearing coaxing with the clamping members 21, the heads 19 of the posts retaining the rotary heads thereon.

The heads are provided with peripheral 10 segmental notches 37 adapted to receive the bobbin carriers 38, these bobbin carriers being provided with cupped upwardly facing keepers 39 which are engaged by the latches 40 having down-turned hooks 41 for securing 15 the carriers to the heads. The latches are mounted for vertical movement in alined holes 42 in the head plates and also project through the holes 43 in the gears. The holes in the gears are also preferably of such size 20 as to serve as bearing supports for the latches.

The latches are provided with laterally projecting arms 44 having pins 45 thereon to receive the springs 46. Alined pins 47 on the upper head plates support the upper ends of 25 the springs. The springs thus serve not only to urge the latches downwardly but to hold them against rotative movement and properly present their hooks in relation to the keepers on the carriers.

30 The latches are provided with laterally projecting cam engaging pins 48 which are preferably of hardened material, the pins of one pair of latches of a head riding upon the outer cam member and the pins of the other 35 pair of latches being shorter and riding upon the inner cam member. The bottom keepers of the carriers serve as supports engaging the bottom head plates, see Fig. 3.

The bobbins designated generally by the 40 numeral 49 are provided with tubular spindles 50 adapted to engage the carriers. The bobbins are provided with thread tensioning members 51, 52 and 53, the member 53 being provided with a tensioning spring 54 45 while the member 51 is provided with a tensioning spring 55. Spools are indicated at 56.

The thread 57 is passed from the spool over the member 51, under the member 52, and through the member 53 so that when the 50 thread is drawn off the member 52 is lifted, thereby lifting the cam-shaped detent release 57. When the thread is broken or a spool exhausted, the member 57' engages the detent 58 of the tappet 59 which is reciprocatingly 55 mounted in the tubular spindle of the bobbin, allowing the tappet to drop down into position to engage the lever 60 which is pivoted at 61 on the bed and provided with an arm 62 engaging the clutch rod 63. This clutch 60 rod is connected to the clutch 13 and arranged through the bed in position to be engaged by the arm 62 which is held yieldingly in engagement therewith by the spring 64.

When one of the tappets 59 is released it is 65 brought into engagement with the releasing

lever and the clutch disengaged, thereby stopping the machine. The carrier latches are timed so that one latch is released and another engaged when the carriers are in supporting engagement with an adjacent pair of heads, 70 so the carriers are effectively supported and transferred from one rotary head to an adjacent head.

I have illustrated and described my improvements in a very practical embodiment. 75 The structure illustrated is made largely of stamping, is strong, rigid and durable although relatively light in weight. The machine is capable of being operated at high speeds with a minimum of noise and vibration. 80

I have not attempted to illustrate various embodiments and adaptations of my invention as it is believed that this disclosure will enable those skilled in the art to which my invention relates to embody or adapt the same as may be desired. 85

Having thus described my invention what I claim as new and desire to secure by Letters Patent is: 90

1. In a braiding machine, the combination with a bed, of an annular series of posts mounted on said bed, heads rotatably mounted on said posts and comprising hubs and vertically spaced plates having alined peripheral notches, coaxing gears arranged on said head hubs below the lower head plates, bobbin carriers having upwardly facing annular keepers, said notches in said heads being adapted to receive said bobbin carriers, rod-like latches mounted in said head plates in radial alinement with their said notches and for vertical reciprocating movement, said latches being arranged through said gears and provided with downwardly fac- 105 ing keeper engaging hooks between said head plates and with laterally projecting arms, springs arranged between the upper head plates and the arms and acting to urge the latches downwardly, the upper head plate and the arms being provided with spring supporting pins, and nested cupped cam members having upwardly facing cams on the edges of their rims, said cam members having coaxing lugs and recesses whereby 110 they are positioned relative to each other, the outer cam members having lugs and the bed plate having coaxing recesses for positioning the pairs of cam members thereon, the posts being provided with clamping members arranged within the inner cams and with nuts arranged below the bed plate, said clamping members constituting thrust bearings for said heads, the latches being provided with laterally projecting cam engag- 115 ing pins. 120

2. In a braiding machine, the combination with a bed, of an annular series of posts mounted on said bed, heads rotatably mounted on said posts and comprising hubs 130

and vertically spaced plates having alined peripheral notches, coacting gears arranged on said head hubs below the lower head plates, bobbin carriers having upwardly facing annular keepers, said notches in said heads being adapted to receive said bobbin carriers, rod-like latches mounted in said head plates in radial alinement with their said notches and for vertical reciprocating movement, said latches being arranged through said gears and provided with downwardly facing keeper engaging hooks, springs acting on said latches, nested cupped cam members having upwardly facing cams on the edges of their rims, said cam members having coacting lugs and recesses whereby they are positioned relative to each other, the outer cam members having lugs and the bed plate having coacting recesses for positioning the pairs of cam members thereon, the posts being provided with clamping members arranged within the inner cams and with nuts arranged below the bed plate, said clamping members constituting thrust bearings for said heads, the latches being provided with laterally projecting cam engaging pins.

3. In a braiding machine, the combination with a bed, of an annular series of posts mounted on said bed, heads rotatably mounted on said posts and comprising hubs and vertically spaced plates having alined peripheral notches, coacting gears arranged on said head hubs below the lower head plates, bobbin carriers having upwardly facing annular keepers, said notches in said heads being adapted to receive said bobbin carriers, rod-like latches mounted in said head plates in radial alinement with their said notches and for vertical reciprocating movement, said latches being arranged through said gears and provided with downwardly facing keeper engaging hooks between said head plates and with laterally projecting arms, springs arranged between the upper head plates and the arms and acting to urge the latches downwardly, the upper head plate and the arms being provided with spring supporting pins, and cams on said bed coacting with said latches.

4. In a braiding machine, the combination with a bed, of an annular series of posts mounted on said bed, heads rotatably mounted on said posts and comprising hubs and vertically spaced plates having alined peripheral notches, coacting gears arranged on said head hubs below the lower head plates, bobbin carriers having upwardly facing annular keepers, said notches in said heads being adapted to receive said bobbin carriers, rod-like latches mounted in said head plates in radial alinement with their said notches and for vertical reciprocating movement, said latches being arranged through said gears and provided with downwardly facing keep-

er engaging hooks, springs acting on said latches, and cams on said bed coacting with said latches.

5. In a braiding machine, the combination with a bed, of series of posts mounted on said bed, heads rotatably mounted on said posts and comprising hubs and vertically spaced plates having alined peripheral notches, coacting gears arranged on said heads, bobbin carriers having keepers, said notches in said heads being adapted to receive said bobbin carriers, rod-like latches mounted in said head plates for vertical reciprocating movement, said latches being provided with downwardly facing keeper engaging hooks between said head plates and with laterally projecting arms, springs arranged between the upper head plates and the arms and acting to urge the latches downwardly, the upper head plate and the arms being provided with spring supporting pins, and nested cupped cam members mounted on said bed to coact with said latches.

6. In a braiding machine, the combination with a bed, of series of posts mounted on said bed, heads rotatably mounted on said posts and comprising hubs and vertically spaced plates having alined peripheral notches, coacting gears arranged on said heads, bobbin carriers having keepers, said notches in said heads being adapted to receive said bobbin carriers, rod-like latches mounted in said head plates for vertical reciprocating movement, said latches being provided with downwardly facing keeper engaging hooks, and nested cupped cam members mounted on said bed to coact with said latches.

7. In a braiding machine, the combination with a bed, of series of posts mounted on said bed, heads rotatably mounted on said posts and comprising vertically spaced plates, coacting gears on said heads, bobbin carriers having upwardly facing keepers, said head plates being peripherally notched to receive said bobbin carriers, reciprocating latches mounted on said heads and provided with downwardly facing keeper engaging hooks between said head plates and with laterally projecting arms, springs arranged between the upper head plates and the arms and acting to urge the latches downwardly, the upper head plates and the arms being provided with spring supporting pins, and nested cupped cam members having upwardly facing cams on the edges of their rims, said cam members having coacting lugs and recesses whereby they are positioned relative to each other, the outer cam members having lugs and the bed plate having coacting recesses for positioning the pairs of cam members thereon, the posts being provided with clamping members arranged within the inner cams and with nuts arranged below the bed plate, said clamping members constituting thrust bearings for said heads, the latches being pro-

vided with laterally projecting cam engaging pins.

8. In a braiding machine, the combination with a bed, of series of posts mounted on said bed, heads rotatably mounted on said posts and comprising vertically spaced plates, coacting gears on said heads, bobbin carriers having cupped upwardly facing keepers, said head plates being peripherally notched to receive said bobbin carriers, reciprocating latches mounted on said heads and provided with downwardly facing keeper engaging hooks, and nested cupped cam members having upwardly facing cams on the edges of their rims, said cam members having coacting lugs and recesses whereby they are positioned relative to each other, the outer cam members having lugs and the bed plate having coacting recesses for positioning the pairs of cam members thereon, the posts being provided with clamping members arranged within the inner cams and with nuts arranged below the bed plate, said clamping members constituting thrust bearings for said heads, the latches being provided with laterally projecting cam engaging pins.

9. In a braiding machine, the combination with a bed, of series of posts mounted on said bed, heads rotatably mounted on said posts and comprising vertically spaced plates, coacting gears on said heads, bobbin carriers having upwardly facing keepers, said head plates being peripherally notched to receive said bobbin carriers, reciprocating latches mounted on said heads and provided with downwardly facing keeper engaging hooks between said head plates and with laterally projecting arms, springs arranged between the upper head plates and the arms and acting to urge the latches downwardly, the upper head plate and the arms being provided with spring supporting pins, and actuating cams for said latches.

10. In a braiding machine, the combination with a bed, of series of posts mounted on said bed, heads rotatably mounted on said posts and comprising vertically spaced plates, coacting gears on said heads, bobbin carriers having cupped upwardly facing keepers, said head plates being peripherally notched to receive said bobbin carriers, reciprocating latches mounted on said heads and provided with downwardly facing keeper engaging hooks, and actuating cams for said latches.

11. In a braiding machine, the combination with a bed, of posts mounted thereon, heads rotatably mounted on said posts, bobbin carriers, coacting latches on said heads, and nested cupped cam members having upwardly facing cams on the edges of their rims, said cam members having coacting lugs and recesses whereby they are positioned relative to each other, the outer cam members having lugs and the bed plate having coacting recesses for positioning the pairs of cam

members thereon, the posts being provided with clamping members arranged within the inner cams and with nuts arranged below the bed plate.

12. In a braiding machine, the combination with a bed, of posts mounted thereon, heads rotatably mounted on said posts, bobbin carriers, coacting latches on said heads, and nested cupped cam members having upwardly facing cams on the edges of their rims, the outer cam members having lugs and the bed plate having coacting recesses for positioning the pairs of cam members thereon, the posts being provided with clamping members arranged within the inner cams and with nuts arranged below the bed plate.

13. In a braiding machine, the combination with a bed, of posts mounted thereon, heads rotatably mounted on said posts, bobbin carriers, coacting latches on said heads, and nested cupped cam members having upwardly facing cams on the edges of their rims, said cam members having coacting lugs and recesses whereby they are positioned relative to each other, the posts being provided with clamping members arranged within the inner cams and with nuts arranged below the bed plate.

14. In a braiding machine, the combination with a bed, of posts mounted thereon, heads rotatably mounted on said posts, bobbin carriers, coacting latches on said heads, and nested cupped cam members having upwardly facing cams on the edges of their rims, the posts being provided with clamping members arranged within the inner cams and with nuts arranged below the bed plate.

15. In a braiding machine, the combination with a bed, of posts mounted thereon, heads rotatably mounted on said posts, bobbin carriers, coacting latches on said heads, and nested cupped cam members having upwardly facing cams on the edges of their rims, the latches being provided with laterally projecting cam engaging pins.

16. In a braiding machine, the combination with a bed, of posts mounted thereon, heads rotatably mounted on said posts, bobbin carriers, coacting latches on said heads, and nested cupped cam members having upwardly facing cams on the edges of their rims.

17. In a braiding machine, the combination with a bed, of heads rotatably mounted on said bed and comprising vertically spaced plates having peripheral notches adapted to receive bobbin carriers, bobbin carriers having spaced upwardly facing annular keepers, the lower keepers coacting with the lower head plate to support the carriers vertically, latches reciprocatingly mounted in said head plates and provided with downwardly facing keeper engaging hooks and with laterally projecting arms, springs arranged between the upper head plates and the arms and acting to urge the latches downwardly, the

upper head plates and arms being provided with spring supporting pins, and actuating cams for said latches.

18. In a braiding machine, the combination with a bed, of heads rotatably mounted on said bed and comprising vertically spaced plates having peripheral notches adapted to receive bobbin carriers, bobbin carriers having spaced upwardly facing annular keepers, the lower keepers coacting with the lower head plate to support the carriers vertically, latches reciprocatingly mounted in said head plates and provided with downwardly facing keeper engaging hooks, and actuating cams for said latches.
19. In a braiding machine, the combination with a bed, of heads rotatably mounted on said bed and comprising vertically spaced plates having peripheral notches adapted to receive bobbin carriers, bobbin carriers having cupped upwardly facing keepers, latches reciprocatingly mounted in said head plates and provided with keeper engaging hooks and with laterally projecting arms, springs arranged between the upper head plates and the arms and acting to urge the latches downwardly, the upper head plate and arms being provided with spring supporting pins, and actuating cams for said latches.

20. In a braiding machine, the combination with a bed, of heads rotatably mounted on said bed and comprising vertically spaced plates having peripheral notches adapted to receive bobbin carriers, bobbin carriers having cupped upwardly facing keepers, latches reciprocatingly mounted in said head plates and provided with keeper engaging hooks, and actuating cams for said latches.

21. In a braiding machine, the combination with a bed, of heads rotatably mounted on said bed and comprising vertically spaced plates having peripheral notches adapted to receive bobbin carriers, bobbin carriers having annular keepers, latches reciprocatingly mounted in said head plates and provided with keeper engaging hooks, and actuating cams for said latches.

In witness whereof I have hereunto set my hand.

EUGENE HIGGINS.
